UNITED STATES PATENT OFFICE.

RODERICK F. DANFORTH, OF WASHINGTON, DISTRICT OF COLUMBIA.

VAPOR-STOVE.

SPECIFICATION forming part of Letters Patent No. 268,871, dated December 12, 1882.

Application filed May 9, 1882. (No model.)

To all whom it may concern:

Be it known that I, RODERICK F. DANFORTH, a citizen of the United States, residing at Washington, in the District of Columbia, have invented certain new and useful Improvements in Vapor-Stoves, of which the following is a specification, reference being had therein to the accompanying drawings.

My invention relates to certain improvements in apparatus for burning the gas produced from light hydrocarbon liquids—such as gasoline and naphtha—for heating and cooking purposes.

The apparatus embodying my improvements will first be described, and those parts or combinations which constitute the invention will then be designated in the claims.

In the drawings hereto annexed, Figure 1 is a perspective view of a vapor-stove embodying my improvements. Fig. 2 is a section of a leaf, of which one or more are hinged to the stove-top. Fig. 3 is a view of the slide-arm which supports the leaf. Fig. 4 is a side view of the burner, a part being in section. Fig. 5 is a top view of the burner. Fig. 6 is a vertical section of a part of same. Figs. 7 and 8 show the groove and the segmental arm and the means by which the inner end of the arm is supported.

In the drawings hereto annexed, the letter A denotes the oil-fount; b, the pipe leading therefrom to the burners; C, the stand which supports these and all other parts. In the present example the stand is shown provided with two burners, D, which are arranged, as usual, immediately below the stand-top, which is preferably made of cast-iron in the form of open grating. In the drawings this is partially shown by the circular-shaped open-work D', which permits the heat and flame from the burner to pass up to the cooking-vessel which rests upon the top. A leaf, E, is provided on one edge, with one or more hooks, e, which curve laterally from one surface of the leaf, forming a segment of a circle. This hook constitutes one part of a hinge, of which a slot, f, near the edge of the table-top, forms the other part. The hook being entered into the slot from the lower side, the leaf is in no danger of being lifted out. A segment-shaped arm, g, is fitted to slide in a similarly-shaped groove, h, formed in the stand-top, and said arm is

provided at one end with a knob, g', by which it may be grasped to facilitate its movement. By moving this arm out when the leaf is elevated to a horizontal position it serves to sustain the leaf, and by moving the arm back the leaf may be dropped or swung down. The means by which the outer end of the arm is supported is shown in Fig. 7. When the arm is moved back under the table-top its inner end is supported by the lateral projection of a lug, h', attached to the under side of the table-top alongside of the groove h and about midway of its length. The knob g' on the inner end of the arm occupies the groove h, and, besides serving as a grasp, keeps the arm from moving laterally, and thereby retains it upon the aforesaid lug. By making the supporting-arm segment-shaped it affords the advantage of sliding partly around the circular-shaped open-work D' in the top, through which the flame rises.

The burner D is constructed with special reference to adapting it to be used for cooking purposes, the object being to produce four non-luminous flames or jets, which shall be so arranged with respect to each other as to form the four corners of a quadrangle, and by thus being spread to cover a broad surface, will be suited for heating the bottom of a cooking-vessel.

To an inverted T-piece, i, a nozzle-piece, k, is secured. The orifice consists of a fine jet-aperture, l, which is closed by the upwardly-projecting point of a needle-valve, m. A vertical tube, n, is secured endwise to the nozzle and about the jet-aperture, and this tube is provided with air-vents 2. At the upper end of this tube is a single, double, triple, or four-way connection, p, and to each a downwardly-curved flame-tube, q, is attached, the lower ends of these flame-tubes being open, and all entering one large air-supply tube, r, which is closed at the upper end, but open at the lower end to admit air. The lower end should be so constructed that while it admits air portions of it will be in direct contact with the nozzle-piece k, in order thereby to conduct heat to the same. Each flame-tube has a slit, s, in the downwardly-curved part, which is readily made by a saw.

The operation may be described as follows:

The valve *m* is turned to allow a jet of the light hydrocarbon fluid to be thrown into the vertical tube *n*, and the valve is then closed. The fluid may then be ignited by applying a flame 5 to the holes 2. As soon as the parts are sufficiently heated the valve *m* should be opened again, and the jet of fluid, then escaping into the heated tube *n*, will be instantly converted into vapor. Air will then enter the tube *n* 10 through the holes 2 and be mingled with the vapor, and the mixture will pass up the heated tube and out the four branches *p* to the flame-slits 3 in the downwardly-curved tubes. At the same time air, which has entered at the 15 lower end of the large tube *r* and has become heated therein, will have risen and entered the open ends of the curved flame-tubes *q*, and at the points of combustion—to wit, the slits 3—the mixture of air and gas from tube *n* and the 20 heated air from tube *r* will unite and produce an intense heating-flame. These four flames will rise through the open-work *D'* in the stand-top, and will heat any vessel placed thereon. A drip-pan, *L*, is placed below the 25 burners to catch drippings of fluid from the burners. The legs of the stand are provided

with rollers or casters *S* to facilitate the movement of the apparatus.

Having described my invention, I claim and desire to secure by Letters Patent of the United States—

1. The combination, with the stove-top provided with a segment-shaped groove, *h*, of a leaf, *E*, hinged to the top, and a segment-shaped arm, *g*, arranged to slide endwise in the said groove, as set forth.

2. A vapor-stove burner consisting of a nozzle-piece, *k*, a vertical vapor-tube, *n*, secured endwise above the nozzle, an air-supply tube, *r*, closed at its upper end and open at its lower end and surrounding the vertical vapor-tube, and one or more downwardly-curved flame-tubes, *q*, one end of which connects with the vertical vapor-tube and the other end with the air-supply tube, as shown and described.

In testimony whereof I affix my signature in presence of two witnesses.

RODERICK F. DANFORTH.
